B. MOLSBERGER

RENEWABLE BROOM

Filed Aug. 6, 1923

Leodaius

WITNESS:

Bernard Molsberger INVENTOR
BY *Victor J. Evans* ATTORNEY

UNITED STATES PATENT OFFICE.

BERNARD MOLSBERGER, OF FORT SAM HOUSTON, TEXAS.

RENEWABLE BROOM.

Application filed August 6, 1923. Serial No. 655,997.

To all whom it may concern:

Be it known that I, BERNARD MOLSBERGER, a citizen of the United States, residing at Fort Sam Houston, in the county of Bexar 5 and State of Texas, have invented new and useful Improvements in Renewable Brooms, of which the following is a specification.

This invention relates to brooms and has for its object the provision of a broom structure which may be called renewable inasmuch as it includes a head designed for permanent retention and use and so constructed as to clamp a bundle of broom straw to form the complete broom, the broom straw or 15 other material being removable and replaceable by a new bundle when excessively worn.

An important object is the provision of a broom of this character which will be simple and inexpensive in manufacture, a great 20 economizer and a general improvement in the art.

With the above and other objects and advantages in view the invention consists in the details of construction to be hereinafter 25 more fully described and claimed and illustrated in the accompanying drawings in which:

Figure 1 is a front elevation of a broom constructed in accordance with my invention,

Figure 2 is a vertical section therethrough taken through the center,

Figure 3 is a cross section on the line 3—3 of Figure 1,

Figure 4 is a detail section showing the 35 mounting of one of the clamps and

Figure 5 is a perspective view of one clamping member.

Referring more particularly to the drawings I have shown my device as comprising 40 a hollow head 10 constructed of suitable material preferably metal and which might be a casting or stamping as preferred, and which may moreover be finished in any desired manner to have a pleasing appearance and to avoid rusting or corrosion. At its top this head is formed with a threaded socket 11 which receives the threaded lower end of a suitable handle 12. In conjunction

50 with this head I make use of a bundle 13 of broom straw or other material of a like nature, which bundle is sewed at 14 in the customary manner with cord or the like to hold the fibers together, though it should be distinctly understood that this bundle or broom

proper is not as elaborate in its formation as the conventional broom head.

For holding the broom head proper within the holder, I provide a pair of elongated clamping plates 15 provided with teeth 16 60 which will bite into the broom head or material for obtaining a firm grip thereon. It is to be noted that the ends of these clamping members are curved so as to conform substantially to the cross sectional configuration of the broom head or bundle. Screwed through the sides of the holder 10 are screws 17 provided at their outer ends with handles 18 and having their inner ends reduced as shown at 19 and threaded as indicated at 20. 70 The outer sides of the clamping members 15 are formed with hollow bosses 21 having threaded holes 22 therein.

In assembling the clamping members, the screws 17 are turned so that the threaded 75 ends 20 thereof will be screwed through the holes 22 and will then be passed entirely therethrough with the threaded ends located within the hollow bosses and the reduced neck portions 19 passing through the holes 80 22. This is the equivalent of a swivel connection and will permit adjusting of the screws 17 in or out as the case may be without disconnecting them from the clamping members. The broom head proper 13 is 85 clamped between the members 15 and is held firmly by screwing in the screws 17. The broom is of course used in the same manner as any other but has the great advantage that when the broom proper becomes worn 90 out it may be replaced with a new one after loosening the screws 17. In this way it is quite obvious that the device will be very economical in use especially in such places where large numbers of brooms of ordinary 95 construction are employed and discarded each week.

While I have shown and described the preferred embodiment of the invention it is of course to be understood that I reserve the 100 right to make such changes in the form, construction and arrangement of parts as will not depart from the spirit of the invention or the scope of the subjoined claims.

Having thus described my invention I 105 claim:

1. A device of the character described comprising a hollow holder formed with a socket for engagement upon a handle, a broom head disposed within the holder, a 110

pair of elongated clamping plates within the holder at opposite sides of the broom head, and screws threaded through opposite sides of the holder and engaging said plates for holding the same in clamping relation to the broom head.

2. A broom structure comprising a holder of hollow formation provided with a socket carrying a handle, a sewed bundle of broom straw constituting a broom head proper disposed within the holder, a pair of elongated clamping plates located within the holder in engagement with opposite sides of the broom head, and screws threaded through the holder and having a swivel connection with the clamping plates.

3. A device of the character described comprising a hollow holder formed with a socket for engagement upon a handle, a broom head disposed within the holder, a pair of elongated clamping plates within the holder at opposite sides of the broom head, and screws threaded through opposite sides of the holder and engaging said plates for holding the same in clamping relation to the broom head, said plates being formed throughout their lengths with ridges biting into the broom head for preventing shifting thereof and the ends of said plates being curved toward each other.

In testimony whereof I affix my signature.

BERNARD MOLSBERGER.
